UNITED STATES PATENT OFFICE.

HANS HENRIK BLACHE, OF COPENHAGEN, DENMARK.

DIESEL MOTOR.

Application filed November 28, 1919, Serial No. 341,230, and in Denmark February 9, 1918.

In Diesel motors in which the valves are moved by means of levers pivoted on a common shaft and operated by cams on a cam shaft it is customary to place the levers of the fuel valve and the starting valve on a sleeve on said shaft so that the levers have different eccentricities as to greatness and position on the sleeve and hence in relation to the shaft. Furthermore in the known constructions the sleeve is provided with a lever carrying a handle which may be manually set into different positions corresponding to the different positions of the sleeve thus obtaining that—

- 15 (1) The starting valve works while the fuel valve is out of action.
- (2) Both valves are out of action.
- (3) The starting valve is out of action while the fuel valve works.

20 This invention now relates to an arrangement by which the setting of the handle is effected automatically by the pressure of the starting air. In multi-cylinder motors, the improved arrangement enables all cylinders or groups of cylinders to be easily set from starting to igniting position in such a manner that the starting valves are closed before the fuel valves are opened so that the resulting ignitions can not enter 25 the starting valves.

30 A constructional form of the invention is shown in the drawing.

Fig. 1 is a vertical section on line 1—1 of Fig. 2.

35 Fig. 2 is a plan view of the cover plate of a cylinder with appurtenant parts.

Figs. 3 and 4 show the levers of the starting and fuel valves, respectively, on a larger scale.

40 Fig. 5 is an enlarged detail section on line 5—5, Fig. 2.

a and *b* are the starting and fuel valves, respectively, of the cylinder which are both held on their seats by springs *d*, *c* and connected by means of bars *f*, *e* to levers *h*, *g* pivoted on a fixed shaft *i*.

45 The levers *g*, *h* carry rollers *j*, *k* to engage the cams *m*, *n* of the cam shaft *l*. When the latter is rotated by the motor the cams are pressed against the rollers whereby the levers *g*, *h* are oscillated and the valves closed and opened. The levers *g* and *h* are directly mounted on a sleeve or movable fulcrum element *p* (see Fig. 5) rotatably mounted on the shaft *i* and having two eccentric portions in mutually-displaced relation, each such portion

forming a fulcrum for one of said levers. A lever *o* is rigidly connected to sleeve *p* so that the latter is turned about shaft *i* when lever *o* is turned. Consequently, when the lever *o* is turned, the centres of oscillation of the levers *g* and *h* will be raised or lowered in such a manner that when the centre of oscillation of the lever *g* is raised, then the centre of oscillation of the lever *h* is lowered and vice versa. By this arrangement the rollers *k* and *j* are brought into or out of engagement with their corresponding cams *n* and *m* respectively.

Fig. 3 shows the sleeve in the position in which the starting valve works. The centre *g* of the eccentric sleeve is in its lowermost position. The lever *o* is in its uppermost position when the lever *h* is in the position shown in Fig. 3 in which the roller *k* is influenced by the cam *n* so that the starting valve will work.

Fig. 4 shows the corresponding position of the fuel valve lever. The eccentricity of the sleeve *p* here is different at least as regards the direction from what it is at the starting valve. The centre *r* of the sleeve here is in its uppermost position which is also the case with the lever *o* which is in the same position as in Fig. 3. In this position of the lever *o* the roller *j* is in its uppermost position where it is completely free of the cam *m* so that the fuel valve will not work.

If the lever *o* is turned to the position *o'*, Figs. 3 and 4, the levers *h*, *g* will be moved into the positions shown in dotted lines. In these positions the lever *h* of the starting valve is raised so that the roller *k* is free of the cam *n*, the centre *g* of the eccentric sleeve around which the lever oscillates being raised to the position *g'*. The starting valve, therefore, will leave off working.

On turning the lever *o* into the position *o'* the lever *g* of the fuel valve will be lowered thus bringing the roller *j* into engagement with the cam *m* because of the centre *r* of the eccentric sleeve around which the lever *g* oscillates being moved to its lowermost position *r'*. Hence it follows that the fuel valve starts working.

In the known devices the said setting of the lever *o* was carried out by hand.

By the present invention a device is provided for effecting automatically this setting of the lever *o* by means of the compressed air supplied to the motor.

On the cover of the cylinder a small cylinder *s*, Fig. 1, is placed in which a spring *t* presses down a piston *y* connected by a bar *u* with the lever *o* of the eccentric sleeve *p*,

5 Figs. 3 and 4. The cylinder *s* communicates through the channel *v* with the channel *w* supplying compressed air to the starting valve *a*. When the spring *t* keeps the piston and therewith the lever *o* in their lowermost 10 position the levers *g*, *h* will occupy the positions shown in dotted lines in Figs. 3 and 4 so that, as above said, the starting valve will be out of working, while the fuel valve works.

15 When compressed air flows through the channel *w* a portion of it will also simultaneously pass through the channel *v* to the cylinder *s* and raise the piston *t* thereby setting the lever *o* in its uppermost position, 20 i. e. the levers *g*, *h* will occupy the positions shown in Figs. 3 and 4 in which the starting valve works while the fuel valve is out of operation. At the opening of the starting valve the motor is started and kept running by the pressure air, the starting valve only working so that no ignition will take place. When the motor has obtained the necessary speed the compressed air is shut off and consequently the spring *t* presses the 25 piston *y* on to the bottom of the cylinder *s*. Hereby the lever *o* goes to its lowermost position and simultaneously the lever *h* of the starting valve is raised so that its roller becomes free of the cam while the lever *g* 30 of the fuel valve is lowered so that its roller engages its cam whereby the fuel valve functions and the ignitions will commence.

I claim—

1. In a Diesel engine, the combination, 40 with a cylinder, separate starting and fuel valves therefor, and an operating lever for each valve; of a cam shaft; a pair of cams thereon, one for each lever; a rotatable supporting shaft having two eccentric portions in mutually-displaced relation, each forming a fulcrum for one of said levers; and means controlled by the starting air supplied to the engine for automatically shifting the rotatable supporting shaft from one position to another so as to simultaneously move one lever into, and the other lever out of, operative 45 position with relation to their respective cams.

2. In a Diesel engine, the combination, 55 with a cylinder, separate starting and fuel valves therefor, and an operating lever for each valve; of a cam shaft; a pair of cams thereon, one for each lever; a movable fulcrum element having two eccentric portions in mutually-displaced relation, each forming a fulcrum for one of said levers; and means controlled by the starting air supplied to the engine for automatically shifting the fulcrum element from one position to another 60 so as to initially move the starting lever in-

to active position and the fuel lever into inactive position with relation to their respective cams, and to thereafter reverse the activity of said levers.

3. In a Diesel engine, the combination of a 70 cylinder; and separate starting and fuel valves therefor; a separate operating lever for each valve; operating means individual to each lever; a rotatable supporting element having two eccentric portions in mutually- 75 displaced relation, each forming a fulcrum for one of said levers; and means controlled by the starting air supplied to the engine for automatically rotating said supporting element so as to change the relation of said 80 fulcrum portions to the respective levers and the consequent activity of said levers relative to their respective operating means.

4. In a Diesel engine, the combination of a cylinder, and separate starting and fuel 85 valves therefor; a separate operating lever for each valve; operating means individual to each lever; a rotatable supporting element having two eccentric portions in mutually- 90 displaced relation, each forming a fulcrum for one of said levers; an actuating member connected to said supporting element to rotate the same so as to change the relation of said fulcrum portions to the respective levers and the consequent activity of said levers 95 relative to their respective operating means; and means controlled by the starting air supplied to the engine for automatically operating said actuating member.

5. In a Diesel engine, the combination, with 100 a cylinder, separate starting and fuel valves therefor, and an operating lever for each valve; of a cam shaft; a pair of cams thereon, one for each lever; a movable fulcrum element having two different eccentric portions whereon said levers are directly mounted; and means controlled by the starting air supplied to the engine for automatically shifting the fulcrum element from one 105 position to another to govern the capability 110 of the two levers to be operated by their respective cams.

6. In a Diesel engine, the combination of a cylinder; separate starting and fuel valves therefor; separate operating means for each 115 valve; and means controlled by the starting air supplied to the engine for automatically rendering one operating means active and the other inactive.

7. In a Diesel engine, the combination of a cylinder; separate starting and fuel valves therefor; separate operating means for each valve; and means controlled by the starting air supplied to the engine for automatically controlling the activity of the two operating means in reverse relation to each other.

8. In a Diesel engine, the combination of a cylinder; separate starting and fuel valves therefor; separate operating means for each 120

valve; and means controlled by the starting air supplied to the engine for automatically rendering the starting valve operating means alternately active and inactive, and 5 the fuel valve operating means alternately inactive and active.

9. In a Diesel engine, the combination of a cylinder, and separate starting and fuel valves therefor; a separate operating lever 10 for each valve; operating means individual to each lever; a movable element having fulcrum means with which said levers immediately co-act; an actuating member connected to shift said element so as to vary 15 the position of said fulcrum means relative to said levers and the consequent activity of the levers relative to their respective operating means; and means controlled by the starting air supplied to the engine for automatically operating said member. 20

10. In a Diesel engine, the combination of a main cylinder provided with separate starting and fuel valves, and with an air-supply channel leading to the starting 25 valve; separate operating means for each valve; a device for controlling the activity of the two operating means; an auxiliary

cylinder mounted on the main cylinder and having an air-supply channel leading to it from the first-named channel to permit a portion of the starting air to be delivered to the auxiliary cylinder; and a piston in the auxiliary cylinder automatically operated by such air and connected to said controlling device to actuate the same when so operated. 30 35

11. In a Diesel engine, the combination of a main cylinder provided with separate starting and fuel valves, and with an air-supply channel leading to the starting valve; separate operating means for each 40 valve; a rotatable controlling device for governing the operativeness of the two operating means; an auxiliary cylinder mounted on the main cylinder and having an air-supply channel leading to it from the first-named channel to permit a portion of the starting air to be delivered to the auxiliary cylinder; and a piston in the auxiliary cylinder automatically operated by such air and connected to said controlling device to 45 rotate the same when so operated. 50

In testimony whereof I affix my signature.

HANS HENRIK BLACHE.
